UNITED STATES PATENT OFFICE.

LOUIS BROUX AND RENE GREGOIRE, OF DOUAI, FRANCE.

APPARATUS FOR CLEANING THE INTERIORS OF CASKS OR LIKE RECEPTACLES.

SPECIFICATION forming part of Letters Patent No. 746,785, dated December 15, 1903.

Application filed February 24, 1903. Serial No. 144,805. (No model.)

To all whom it may concern:

Be it known that we, LOUIS BROUX and RENE GREGOIRE, citizens of the Republic of France, residing at Douai, Nord, France, have invented certain new and useful Improvements in or Relating to Apparatus for Cleaning the Interiors of Casks or Like Receptacles, of which the following is a specification.

10 The present invention relates to an apparatus for cleaning the interiors of casks and like receptacles.

The apparatus comprises a brush or the like mounted on a rod capable of being oscillated 15 in all directions in the interior of the cask, a point of support being arranged in the middle of the cask, the movements of the brush being effected by a lever worked from the outside.

20 In the accompanying drawings, Figure 1 is a longitudinal section of a cask in which our apparatus is arranged, and Fig. 2 is a modification of the apparatus shown in Fig. 1.

The apparatus, as shown in Fig. 1, is composed of a central rod or support *a*, which is introduced into the bung-hole of the cask and fixed in position by means of a clamp *e*, provided with a screw *v*, traversing an angle-arm *f*, which is integral with the central rod *a*, 25 this angle-arm on the outside of the cask forming a counterpart of another arm *g*, also integral with the central rod *a* and constituting the other clamp member resting against the inside of the cask.

30 The central rod *a* carries at its lower part a swivel loop or ring *h*, capable of turning in the former and of oscillating relatively to this rod, owing to it being fitted loosely in the rod to which it is attached. A spring *r* may, if 35 desired, be provided on the rod *a* above the ring *h* in order to facilitate the movements of the latter and to prevent it becoming jammed.

A bar *i*, forming the handle of a brush *k* at 40 its outer end, passes through the ring *h*, the brush being attached to the bar by means of a collar or clip *j*, so that it can be easily detached and replaced by another.

The end of a lever *l*, passing through the 45 bung-hole and provided with a handle *m*, is hinged at *o* to the handle *i* near the brush. This lever passes through a collar *c*, which is

secured to the outer arm *f* of the central rod *a* by means of a pin *d*, serving at the same time as a key for turning the clamping-screw *v*. The collar *c* thus arranged protects the edge of the bung-hole against the shocks it would undergo in consequence of the movements of the operating-lever *l*.

In most cases the bung-holes being of a determined diameter, the collar *c* can be integral with the central rod *a*, as shown in Fig. 2, and fit directly in the said hole instead of and in the place of the ordinary bung. The construction in such cases is more simple and 65 does not require a set-screw *v* to fix the device in place.

After having successively introduced the brush *k* of the bar *i* and the lever *l* into the cask, taking care to cause the end of the bar *i* to pass through the ring *h*, and after having secured the central rod *a* in position the operator presses on the lever in such a manner that the brush will pass over the whole interior of the cask, rubbing it vigorously, 75 and thereby cleaning it. He operates first of all on the part of the cask between the center and one of the heads. Then by turning the central rod round by giving a lateral semi-circular movement he cleanses the second 80 half of the cask from the center to the other head. He then withdraws the apparatus from the cask in the opposite order to that adopted for introducing it, and he has only to brush the inner part of the bung-hole with an ordinary bent brush and to rinse.

In order to adapt this apparatus to casks of different dimensions, the central rod *a* and the brush-handle *i* can be telescopic or divided into two parts, sliding one on the other 90 in such a manner that the ring *h* can be placed in the center of the cask to be cleaned and that the handle *i* of the brush *k* can be of the required length.

What we claim as our invention, and desire to secure by Letters Patent, is—

1. Apparatus for cleaning the interiors of casks and like receptacles comprising a collar adapted to enter the bung-hole of the cask, an arm depending from said collar, a swivel-loop on the end of said arm, a brush-handle passing through said loop and an operating-lever extending through the collar and hinged to the brush-handle.

2. Apparatus for cleaning the interiors of casks and like receptacles, comprising a collar adapted to enter the bung-hole of the cask, an arm depending from said collar, a swivel-loop on the end of said arm, a spring connection between the depending arm and swivel-loop, a brush-handle passing through said loop and an operating-lever extending through the collar and hinged to the brush-handle.

3. Apparatus for cleaning the interiors of casks and like receptacles, comprising a collar adapted to enter the bung-hole of the cask, an extensible arm depending from said collar, a swivel-loop on the end of said arm, a brush-handle passing through said loop and an operating-lever extending through the collar and hinged to the handle near the brush end thereof.

4. Apparatus for cleaning the interiors of casks and like receptacles, comprising a collar adapted to enter the bung-hole of the cask, an arm depending from said collar, a clamp for securing said collar and arm to the cask, a swivel-loop on the end of said arm, a brush-handle passing through said loop and an operating-lever extending through the collar and hinged to the handle near the brush end thereof.

In testimony whereof we have signed our names to this specification in the presence of two subscribing witnesses.

LOUIS BROUX.
RENE GREGOIRE.
